RECOIL CHECK AND BARREL ACCELERATOR
FOR AUTOMATIC WEAPONS

Samuel G. Green, Gray, Ga.

Application November 2, 1939, Serial No. 302,553

9 Claims. (Cl. 89—14)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to a recoil check and barrel accelerator for machine guns and similar automatic weapons of the moving barrel type.

The purpose of this invention is to provide a recoil and barrel accelerator for barrels of the recoiling type which is especially adapted to perform its normal function independently of the guide bearing for the muzzle end of the barrel.

In the prior art, barrel accelerators have been used in conjunction with recoiling barrels wherein in the guide bearing for the muzzle end of the barrel formed an integral part of a accelerator chamber, this arrangement, however, presents serious disadvantages due to the fouling of the barrel portion exposed to the gases in the acceleration chamber with consequent seizure of the barrel by the muzzle guide bearing and accompanying inoperation of the weapon. This disadvantage may not be eliminated by increasing the clearance between the barrel and barrel guide bearing for if the clearance is made sufficiently large to overcome the difficulty the gun will be rendered inaccurate because of the improper bearing and therefore guiding relation between the guide bearing and barrel.

It is an object of this invention to provide a barrel accelerator organized to form a guide bearing for the muzzle end of the barrel that will not be subjected to the corrosive and fouling effect of the gases collected in the acceleration chamber.

It is a further object of the invention to temporarily confine the gases of each explosion in an acceleration chamber and utilize them to accelerate the normal recoil of the barrel through a piston effect upon the muzzle end of the barrel without likelihood of seizure of the muzzle of the barrel by the walls of the acceleration chamber through fouling.

It is still a further object of the invention to increase the energy of recoil of the barrel by functionally increasing the cross sectional area of the muzzle of the barrel acted upon by the gases collected in the acceleration chamber.

A still further object of the invention is to employ a deflection disk and recoil check in serial relation with the accelerator.

Another object is to provide a free discharge opening rearwardly and forwardly of the boosting chamber to eliminate pre-ignition and flash of unburned gases or other combustibles and to avoid

the heating and fouling effect of gases trapped by restricted discharge openings.

Still another object is to provide a barrel bearing with minimum bearing contact; such as a needle point or spline bearing, to aid in avoiding heat transfer and consequent binding of the barrel by expansion.

The specific nature of the invention as well as other objects and advantages thereof will clearly appear from a description of a preferred embodiment as shown in the accompanying drawing in which:

Fig. 1 is a view in longitudinal section of the recoil check and barrel accelerator of this invention attached to the muzzle of an automatic weapon of the recoiling barrel type.

Fig. 2 is a section taken on the line 2—2 of Fig. 1.

Fig. 3 is a section taken on the line 3—3 of Fig. 1.

Fig. 4 is a longitudinal sectional view of the muzzle portion of a modified barrel showing how a barrel may be formed to be received in direct bearing relation to the muzzle bearing.

Referring now to the drawing by characters of reference and more particularly to Fig. 1 there is shown the muzzle end of a recoiling barrel 10 disposed within a barrel jacket 11 as is well understood in the art.

A cylindrical barrel guide sleeve 12 of suitable heat resistant substance provided with an inwardly directed flange 13 at its rear end and an interiorly threaded reduced bore 14 at its forward end is sleeved over the muzzle of the barrel 10 with the flange 13 engaging the exterior of the barrel and the reduced threaded bore 14 secured to the barrel through interthreaded engagement with exterior threads 15 on the muzzle end of the barrel. In this manner a gas sealed joint is effected between the muzzle of the barrel and the sleeve. The cylindrical portion of the guide sleeve 12 is disposed in non-contacting relation with the barrel whereby conduction of heat between the guide sleeve and barrel is reduced to a minimum. The exterior forward end of the sleeve 12 is of reduced diameter as indicated at 16 for a purpose made apparent hereinafter. While it is preferable to use a guide sleeve as explained it will of course be understood that the barrel itself may be used as the guide surface; in which case the sleeve 12 shown could be considered an integral part of the barrel functionally, and the muzzle portion of the barrel 10' would be formed as shown in Fig. 4 to be directly re-

ceived by the bearing 19 hereafter described in greater detail.

A housing for the acceleration and recoil check gas chambers comprising a generally cylindrical tubular member 17 is secured to the muzzle end of the jacket 11 in any suitable manner. In the form of the invention disclosed the rear portion of the member 17 is inserted within the muzzle end of the jacket 11 to a position where its rear end is in substantial registration with the flange 13 of sleeve 12 and is secured to the jacket as by the threads 18, although it will of course be obvious that any conventional locking means may be employed to effect the desired interlocked relation between the jacket 11 and member 17. Adjacent the rear end portion of the member 17 an interiorly disposed guide bearing 19 is provided to slidably receive the cylindrical bearing portion of the guide sleeve 12 in bearing and guiding relation throughout the positions of the barrel between battery and recoil.

Due to the relationship of the barrel guide bearing to the acceleration gas chamber herein subsequently described the guide bearing 19 may be relieved of full bearing engagement with the barrel guide sleeve 12 as indicated at 20 in Fig. 2 in order to reduce the friction between the guide sleeve and bearing to the least practical minimum, and to prevent the trapping of any gases of combustion that would cause fouling of the bearing surface.

Intermediate its rear end and median portion the member 17 is formed to provide a plurality of radial circumferentially spaced gas emission ports 21 so disposed as to normally be covered by the barrel guide sleeve 12 in and from the battery position of the barrel 10 to a predetermined recoil position of the barrel. Conveniently the ports 21 may be formed in a section of member 17 of exteriorly increased radial section to facilitate the provision of an annular shoulder or abutment 22 adapted to abut the muzzle end of jacket 11 for the purpose of properly positioning the member 17 within the jacket 11 during assembly thereon as above described and retaining the member within the jacket against breechwise movement. A second annular shoulder or abutment 23 is also formed forwardly of the shoulder 22 for positioning a deflection disk to be later described.

The barrel recoil acceleration gas chamber 24 is formed by the muzzle end or face of the barrel 10 and sleeve 12, a cylindrical tubular element or ring 25 inserted within the member 17 and a centrally bored cup-shaped member 26 also inserted within member 17 with its concavity confronting the muzzle of the barrel. The element 25 is made of high heat resistant substance capable of retaining a substantial percentage of its cold hardness when subjected to high temperature, such for example as Stellite, and is inserted within member 17 in abutting engagement with an interiorly disposed annular shoulder 27 in such manner as to encompass the cylindrical portion 16 of sleeve 12 in the battery position of the barrel and during a predetermined recoil travel of the barrel. Preferably the clearance 28 between the sleeve portion 16 of sleeve 12 and ring 25 is substantially four times as great as the clearance between the bearing surfaces of sleeve 12 and guide bearing 19. The comparatively great clearance between the sleeve and ring 25 in conjunction with the high polish maintained by the Stellite ring will be sufficient to by-pass any unburned particles carried by the gases of explosion.

into the acceleration chamber 24 past the sleeve through the clearance 28 to atmosphere by way of ports 21 without any tendency of the particles to bind between the sleeve and ring in the clearance 28. While the clearance 28 would be impractical where, as in the prior art the ring 25 has also served as a guide bearing for the barrel, it is admirably adapted to the organization of the accelerator of this invention and although the clearance 28 is sufficient to permit the exhaust of the heavy particles carried in the gases of explosion without tendency of seizure of sleeve 12 by the ring 25 the clearance is sufficiently small to throttle the gas that escapes from the acceleration chamber 24 and thereby retard reduction of pressure in the chamber 24 until the gas has imparted a predetermined amount of energy to the barrel for the purpose of accelerating its recoil. The increased clearance 28 is offset by the increase of the area of the barrel functionally effected by the forward end 29 of sleeve 12 against which the gas expands as well as the end of the barrel to drive the barrel in recoil after the manner in which gas acts on a piston in an internal combustion engine. To insure against any fouling collecting on the sleeve portion 16 the interior of ring 25 is formed with one or more clearance grooves 30 which operate in a well known manner. Although the invention as shown embodies a separate ring 25 as preferable because of the ease of replacement, it will of course be understood that member 17 or cup 26 may be formed to include the ring 25 if desired.

As shown in the drawing the base 31 of the cup 26 is formed to abut the forward end of the ring 25 in substantially sealed relation and the disc is provided with an axial passage 32 disposed in prolongation with the bore of the barrel to form a projectile passage.

Forwardly of the disc 26 the member 17 is provided with a plurality of circumferentially spaced exhaust ports 33 of generally rectangular configuration having forwardly and inwardly inclined end defining walls. The forward face of the cup 26 is cut away inwardly from its periphery to form an annular seat 34 and a tubular insert 35 formed with ports 36 of the same configuration as the ports 33 and adapted to register therewith is inserted within the member 17 in abutting relation with the seat 34.

The recoil check gas chamber 37 is formed by the cup 26, insert 35 and an end closure plug 38. As shown the plug 38 is axially bored at 39 to form a projectile passage and is provided with a conical concavity 40 on its inner face generally parallel with the outer conical face of cup 26. The peripheral portion of the inner end of the plug 38 is cut away to form an annular shoulder 41 adapted to abut the outer end of insert 35 and the plug is secured to the member 17 through interthreaded engagement or in other suitable manner as indicated at 42 with shoulder 41 abutting the outer end of insert 35 to retain the elements 25, 26 and 35 in proper position within member 17. The plug 38 is locked in proper interthreaded relation with member 17 by a lock screw 42 or similar expedient. The spacing of plug 38 from cup 26 is so chosen as to permit discharge of the gases from chamber 37 through the parts 36 and 33 at relatively low velocity. In discharging from chamber 37 the gases will impinge upon the forward defining walls of ports 38 and 33 as well as the plug 38 thus increasing the area upon which the gases work in a counter-recoil direction, which area in the present case

is designed to be approximately 27 times the area of the bore of the weapon. This gives an area upon which the gases work in a counterrecoil direction substantially 5 times the area used for similar purpose in the prior art recoil checks of similar design for similar weapons.

To prevent the gases exhausted from chamber 37 from interfering with the gunner in training the gun, a baffle check having a rearwardly diverging baffle 43 and cylindrical interiorly threaded tubular portion 44 is exteriorly threaded on the member 17. A spanner nut 45 may be threaded on member 17 to lock the baffle member 43—44 in position. In addition to controlling the deflection of the gases to the rear the baffle check plate is adjustable to close the ports 36—33 for the purpose of controlling the rate of fire of the weapon. When the ports 36—33 are closed or partially closed the pressure of the gases in chamber 37 are maintained higher for longer periods than when the ports are fully open with the result that the pressures in chamber 24 are also maintained higher for longer periods of time, due to the back pressure in chamber 37, which will increase the working pressure of the gases acting on the barrel and barrel guide sleeve in a recoil direction with consequent acceleration in recoil of these elements. By adjusting the baffle check plate over the ports 36—33 the rate of fire may be nicely adjusted to compensate for different weight projectiles, different powder lots, etc.

As more clearly shown in Fig. 1 the chamber 24 is a relatively small hot chamber made of such size as to avoid expansion of the gases of explosion discharging from the bore of the barrel and preferably so formed as to effect compression of the gases collecting therein so that the temperature of the gases will be maintained or even increased to completely burn unconsumed combustibles carried into the chamber by the gases in order that, flash, smoke, etc., will be reduced to a minimum.

While this invention has been described in connection with an automatic weapon of the recoiling barrel type it is to be understood that the construction is adapted for use with a gas operated fixed barrel type of gun with equal facility by simply cutting the member 17 off forwardly of the ports 21 and securing the barrel to the member 17 through threads cut in member 17 in the area occupied by ring 25. In this case the acceleration chamber may be eliminated if desired.

In the embodiment of the invention shown only one recoil chamber has been shown as it is not essential to resort to the use of multiple chambers where full advantage is taken of the area provided in a single recoil check chamber of the type described for checking the velocity of the gases, however, if desired a multiple series of recoil check chambers may be employed by substantially duplicating the structure of the single chamber shown.

As the recoil check gas chamber is designed to reduce the velocity of the gases exhausted therefrom to a minimum the effect of the gases striking the baffle check plate 43 in a recoil direction will be negligible.

In operation the assembled accelerator and recoil check will be secured to the jacket 11 as shown in Fig. 1 and upon firing the weapon a projectile will be propelled by the gases of explosion of the propellant charge through the bore. When the projectile leaves the bore and enters the passage 32 of cup 26 the gases will collect in chamber 24 and be compressed because of their

momentum and the shape of the chamber. Compression of the gases will increase their temperature and effect combustion of unconsumed combustible particles carried by the gases into the chamber. The gases confined in chamber 24 will act upon the end of barrel 10 and sleeve 12 to accelerate recoil of the barrel by imparting greater energy of recoil thereto. Because of the comparatively large clearance 28 between the ring 25 and sleeve portion 16 any unconsumed particles in chamber 24 will be exhausted by the confined gases in chamber 24 through the clearance 28 to atmosphere by way of ports 21. The clearance 28 is made possible by provision of the bearing 19 which accurately guides the muzzle of the barrel and eliminates all possibility of seizure of the barrel by the ring 25. On the other hand the use of a separate ring 25 or gas check makes it possible to reduce the friction of the bearing 19 on sleeve 12 to a necessary minimum. The clearance grooves 30 in ring 25 will clear any fouling that tends to accumulate on the sleeve portion 16. When the projectile enters the passage 39 the gases remaining in the bore and chamber 24 will enter chamber 37 and expand impinging on the conical surface 40 of plug 38 and the forward defining walls of ports 36 and 33 transmitting a forward or counterrecoil reaction to the member 17 and jacket 11 which will counteract the recoil reaction of the weapon transmitted to the carriage or support for the weapon. As the size of the chamber 37 and working area of the chamber effective to check recoil is so coordinated as to utilize the velocity head of the gases entering the chamber in a maximum counterrecoil reaction the velocity of the gases exhausting through ports 36 and 33 is negligible in so far as the recoil reaction of the gases striking plate 43 is concerned. When it is desired to regulate the rate of fire of the gun it is only necessary to screw the element 44—45 of the baffle check forwardly to partially close the ports 36—33. This will cause the gases to remain in chamber 37 for a longer period of time at a higher pressure and through the back pressure so created likewise causes the gases in chamber 24 to remain at a higher pressure for a longer period of time with consequent greater energy of recoil being imparted to the barrel and accompanying acceleration thereof in recoil.

Having now particularly shown and described what is at present considered a preferred embodiment of the invention what I claim and desire to secure by U. S. Letters Patent is:

1. In a weapon of the type having a recoiling barrel disposed in a spaced surrounding barrel jacket in combination, a tubular member secured to the barrel jacket and surrounding the muzzle portion of the barrel, a guide sleeve surrounding the muzzle portion of the barrel in spaced relation and secured to the muzzle end of the barrel in gas sealed relation, a guide bearing carried by the tubular member for the guide sleeve, a heat resistant ring in said tubular member encompassing the muzzle end of the guide sleeve in the battery position of the barrel, said ring and the muzzle end of the sleeve being so related as to provide a clearance therebetween substantially greater than the working clearance between the guide bearing and guide sleeve, gas exhaust ports formed in the tubular member between said guide bearing and ring, communicating with the ring clearance, and a perforated conical cup in said tubular member with its perforation aligned with the bore of the barrel engaging the ring and forming a gas compression chamber in coopera-

tion with the ring and muzzle end of the barrel and guide sleeve.

2. The structure of claim 1 wherein the guide bearing is relieved to reduce friction and said ring is provided with one or more clearance grooves.

3. In a weapon of the type having a recoiling barrel disposed in a spaced surrounding barrel jacket in combination, a tubular member secured to the barrel jacket and surrounding the muzzle portion of the barrel, a cylindrical guide sleeve secured to the barrel in gas sealed relation at its muzzle end and having a muzzle portion of reduced diameter, a guide bearing carried by the tubular member for guiding the sleeve through its portion of largest diameter, a heat resistant ring in said tubular member encompassing said sleeve through a part of its reduced diametral portion, the diameter of said reduced portion of the sleeve and interior diameter of the ring being related to provide an annular clearance substantially greater than the clearance between the guide bearing and sleeve, gas exhaust ports in said tubular member communicating with the ring clearance and interposed between the ring and guide bearing and means in said tubular member cooperating with the muzzle end of the barrel, sleeve and ring forming a barrel acceleration gas chamber.

4. The structure of claim 3 wherein said ring is provided with one or more clearance grooves adapted to clear the reduced diameter portion of said sleeve of any fouling deposited thereon.

5. In a weapon of the class described, a barrel, a tubular member, means securing the tubular member in operative relation to the muzzle of the barrel, a plurality of circumferentially spaced ports formed in the tubular member forwardly of the muzzle of the barrel, additional ports formed in the tubular member rearwardly of the muzzle of the barrel, a removable closure plug having a projectile passage secured in the forward end of the tubular member and a baffle check plate comprising a cylindrical portion and outwardly extending baffle wall portion adjustably mounted on said tubular member intermediate said first recited and additional ports by means of its cylindrical portion adapted to be adjusted to throttle said first recited ports.

6. In a weapon of the character described, a recoiling barrel, a jacket surrounding said barrel and spaced therefrom, a tubular guide member secured to the jacket and surrounding the muzzle portion of the gun barrel, a guide sleeve carried by the barrel, a ring in said tubular guide member surrounding the muzzle end of the gun barrel when the barrel is in battery position, said ring, the end of the guide sleeve and end of the gun barrel being so related as to provide a clearance between the end of the barrel and the guide sleeve, a cup-shaped member in the tubular member engaging the ring and forming a gas com-

pression chamber in cooperation with the ring and end of the muzzle, and gas exhaust ports in the tubular member connecting with the ring clearance and the gas compression chamber.

7. In a weapon of the type having a recoiling barrel disposed in a spaced surrounding barrel jacket, in combination, a tubular bearing member secured to the jacket and surrounding the muzzle portion of the barrel, a guide sleeve carried by the muzzle portion of the barrel, an abutment in the tubular member, a ring in the tubular member engaging said abutment and surrounding the muzzle end of the barrel, said ring being spaced from the end of the gun barrel to by-pass such solid particles as are carried by the gases to provide a clearance between the ring and barrel, ports in the tubular bearing member communicating with said clearance, a conical disk having a projectile passage therethrough, said disk engaging the ring and cooperating with it and the muzzle end of the barrel to form an acceleration gas chamber, a tubular insert in said tubular bearing member engaging the forward face of the conical disk, registering ports formed in said tubular member and insert, and a closure plug provided with a projectile passage secured in the forward end of the tubular insert and engaging the forward end of said insert for holding the ring, disk and insert in assembled relation in the tubular bearing member and forming a recoil check gas chamber in cooperation with said insert and disk.

8. The invention claimed in claim 7, characterized in that the closure plug is provided with rear walls substantially parallel with the front face of the conical disk, and that the ends of the registering ports in the tubular member and insert are provided with forwardly inclined surfaces in substantial prolongation with the conical surfaces of said disk and plug.

9. In a weapon of the character described, a barrel jacket, a recoiling gun barrel abruptly reduced in diameter at its muzzle end a substantial distance therefrom forming a shoulder adjacent said end, a cup-shaped member having a central projectile opening therethrough, the said member in cooperation with the barrel forming an acceleration chamber, said member being provided with a flange surrounding the reduced portion of the barrel when the said barrel is in battery position, a clearance between said flange and barrel and by-passing such solid particles as are carried by the gases to prevent binding of the barrel, the extreme external diameter of the flange being commensurate with the barrel adjacent the reduced portion, the rear end of the flange terminating short of the shoulder whereby the deflection of the gases is assisted, means in the barrel jacket for supporting and guiding the barrel and gas exhaust ports communicating with said clearance.

SAMUEL G. GREEN.

CERTIFICATE OF CORRECTION.

Patent No. 2,362,996.

November 21, 1944.

SAMUEL G. GREEN.

It is hereby certified that error appears in the printed specification of the above numbered patent requiring correction as follows: Page 4, second column, lines 14 to 16 inclusive, claim 7, for "by-pass such solid particles as are carried by the gases to provide a clearance between the ring and barrel" read --provide a clearance between the ring and barrel to by-pass such solid particles as are carried by the gases--; and that the said Letters Patent should be read with this correction therein that the same may conform to the record of the case in the Patent Office.

Signed and sealed this 30th day of January, A. D. 1945.
